CIRCUIT BREAKERS

Thomas M. Cole, Harrison, N.Y., and Henry S. Wingard, Cranford, N.J., assignors to Federal Pacific Electric Company, a corporation of Delaware

Filed Nov. 12, 1957, Ser. No. 695,708

27 Claims. (Cl. 200—116)

The present application relates to electrical switching devices and more particularly to multi-pole circuit breakers for alternating current.

An object of the present invention is to increase the current-interrupting capacity of multi-pole circuit breakers and the like, particularly of such devices used in alternating current circuits, and a more specific object in this connection is to provide novel contact-operating means effective for that purpose as well as for single-phase current interruption. A further object is to provide novel single-pole and multi-pole circuit breakers having increased peak-current ratings compared to previous circuit breakers of like proportions.

It has been customary to open the contacts of a circuit breaker by fast-acting mechanisms and, in the case of multi-pole circuit breakers, a common mechanism has been arranged to part all of the contacts simultaneously in response to an overload of either short and severe, or long and moderate, character. The present invention is not directly concerned with the latter type of fault, although devices constructed to handle severe overloads in accordance with the present invention may also be arranged to respond to such moderate overloads.

To meet the test of severe current excesses resulting from short circuits, the almost universal approach has been to speed the interruption of the arcs between the contacts as they part, through the use of fast contact-operating mechanisms and quick-acting current-responsive tripping mechanism; and to design arc interrupters capable of quenching arcs developed even at the most unfavorable portion of the alternating current cycle.

If it should happen that the current flowing in a circuit breaker is at or rising toward its peak short-circuit value at the instant that the contacts start to separate, then the ionizing energy to which the contacts of that pole are subjected is most severe, and the ionized gas that is produced may carry the current continuously even with the contacts widely separated and even with carefully designed arc chutes. The final extinction of the arc generally occurs (if at all) during that portion of the alternating current cycle when the current is passing through its zero value irrespective of the time in the current wave when the contacts start to separate. As a result, particularly in a three-phase circuit breaker subjected to a severe three-phase short-circuit, the arc in one of the poles inevitably develops damaging energy during nearly half a cycle; and the ionization due to arcing may be such as to cause restriking of the arc during the succeeding half cycle, and repeatedly thereafter.

Therefore, considering circuit breakers and the like of predetermined arc interrupting capacity, an object of the present invention is to increase the circuit breaker rating so as to operate effectively to interrupt much heavier levels of peak currents developed during short-circuits.

In the detailed description of an illustrative embodiment of the invention appearing below and shown in the accompanying drawings, a multi-pole circuit breaker is provided in which each pole includes an individual elec-

2

trodynamically actuated contact controlling and operating mechanism effective for maintaining the contacts of that pole closed while the contacts carry potentially damaging instantaneous values of current, and for opening the contacts of that individual pole when the alternating current wave is decaying toward zero and has reached a safe reduced and declining value. Even though a short circuit may occur, the instantaneous value of current at that instant may be low due to the portion of the alternating current wave at the instant that the short circuit occurs; and in that event, nothing happens until the current rises to a level sufficient to cause the electrodynamic action to take place. It is therefore highly significant that opening of the contacts depends on there being an instantaneous severe current level during an alternating current wave, and that the opening of the contacts of that pole or phase takes place before that current wave crosses the zero level. It is also significant that each pole in a multi-pole circuit breaker operates independently, in accordance with its own instantaneous current conditions.

In the aforementioned preferred embodiment of the invention, the same electrodynamic structure is used for accomplishing two functions, namely, for holding the contacts of each individual pole together during current excesses and for conditioning the contact-carrying mechanism to part the contacts when the current declines to a safe value for interruption. It will naturally be understood that separate electrodynamic arrangements can be provided for these two functions.

The illustrative multi-pole circuit breaker having the foregoing provisions in each of its poles to hold the individual contact pairs closed during severe current excesses and to condition the individual contact pairs for safe parting is also equipped with a common contact closing and opening mechanism having a current-controlled latched-spring arrangement for opening all of the poles when a severe overload occurs in any of them. The operation of the mechanism to open all of the poles is delayed until after the individual mechanisms of the several poles have had time to interrupt their several currents. In this way, the main operating mechanism does not force open a pair of contacts that, at a particular instant, may be carrying a heavier instantaneous value of current than the circuit breaker can interrupt nor is any circuit interrupted where the current is low but is increasing toward a destructive level.

The nature of the invention together with additional features and objects will be better appreciated and understood from the following detailed disclosure of the illustrative embodiment which is shown in the accompanying drawings forming part of this disclosure. In the accompanying drawings:

Fig. 1 is a side elevation, largely in cross-section of one pole of a multi-pole circuit breaker embodying certain aspects of the present invention;

Fig. 2 is the plan view of a multi-pole circuit breaker each pole of which is constructed according to Fig. 1;

Fig. 3 is the perspective view, with a portion broken away, of a current-carrying element in Fig. 1;

Fig. 4 is the plan view of the element shown in Fig. 3;

Figs. 5, 6, 7 and 8 are somewhat enlarged views of the mechanism in Fig. 1 in various operative configurations thereof;

Fig. 9 is a fragmentary elevation of the common operating mechanism of the multi-pole circuit breaker of Fig. 2;

Fig. 10 is a fragmentary cross-sectional view along the line 10—10 in Fig. 9.

Fig. 11 is a graphic representation of the three-phase operation of the three pole circuit breaker in Figs. 1—10.

The illustrative circuit breaker here shown employs

much of the structure of well-known circuit breakers, such as that shown for example in Patent 2,673,264 issued March 23, 1954, to T. M. Cole (one of the present applicants) that patent being assigned to the assignee of this application.

The multi-pole circuit breaker shown in the accompanying drawings includes in each pole a pair of terminals 10 and 12, an arc chute 14, a pair of contacts including a movable contact 16, a stationary contact 18, and novel means for supporting and individually operating each movable contact 16. A common operating mechanism as shown in Fig. 9 is provided for all of the poles, controlled for automatic release by a common trip bar 20. Individual current-responsive bimets 22 for each of the poles are arranged to operate the trip bar. The bimets act in the usual fashion to trip the circuit breaker after a relatively long interval of sustained moderate overload.

Referring particularly to Fig. 1, each movable contact 16 is carried by a conductive contact-carrying arm 24 as of copper which has a pivot 26 that operates in a slot 28 formed in contact arm 24. Pivot 26 is fixed to a pair of arms 30 forming a contact-arm carrier that is in turn fixed to a square shaft 32 formed of insulation or of metal sheathed in insulation. The portion of arms 30 which flank contact arm 24 adjacent pivot 26 are quite close to each other so as to provide side guides for the movable contact arm 24. Those close-spaced guiding portions of arms 30 are connected by bends (Fig. 1) to the remainder of the arms which are widely spaced to accommodate four over-centering springs 34 and 36 as shown also in Figs. 9 and 10. These springs operate as a form of toggle between respective end pivots 35 of the toggle in arms 30 and pivots 37 in an upstanding ear 38 on a rearward extension of movable contact arm 24 to the left of pivot 26 in Fig. 1, forming the knee of the toggle. Close nearby, movable contact arm 24 has another extension 40 which bears against a stop 42 when the contacts are open in the configuration of Figs. 8. Elements 26, 32 and 42 unite arms 30 into a sturdy supporting and guiding carrier that pivotally supports and bodily moves contact arm 24.

The configuration of the mechanism shown in Figs. 1 and 9 is that corresponding to the normal operating condition with contacts 16 and 18 closed. In that configuration, extension 40 of the movable contact arm 24 is spaced away from the stop 42. The opposite ends of each spring 34 and 36 are compressed toward each other, with the result that portion 38 of movable contact arm 24 is spring-biased upward and counter-clockwise about pivot 26. This firmly but resiliently biases movable contact 16 against fixed contact 18 to provide the usual contact pressure for normal operation.

The corresponding contact-carriers 30 of all of the poles are united by square shaft 32 for operation in unison, as a relatively rigid unitary element. This square shaft is operated by mechanism appearing in Figs. 9 and 10, now to be described. This common operating mechanism is provided for all the poles in the illustrative multi-pole circuit breaker. Alternatively any suitable individual operating mechanisms may be used for each pole with a trip-one-trip-all arrangement and with a common operating handle.

The common operating mechanism is aligned with the center of the three poles and operates contact-arm carrier 30 of that pole directly. This contact-arm carrier operates square shaft 32 which actuates the other contact-arm carriers 30. The center-pole operating mechanism is largely carried by a pair of plates 44 which are anchored to the bottom of the molded insulating enclosure 46. A manual operating lever 48 has a pivotal seat 50 in each of these frame plates 44, so as to swing between the closed-contacts position in Fig. 9 and another position, to the left of that illustrated in Fig. 9, when the contacts are open. A pair of tension springs 52 act

between handle 48 and the pivot or knee 54 of a toggle including a lower toggle links 56 (Fig. 10) and upper toggle links 58. The two lower toggle links 56 have separate pivots 60 to the respective arms 30. Upper toggle links 58 are biased upward against a pivot 62 carried by a cradle or releasable member 64 that is pivoted at 66 in frame plates 44.

A secondary latch 68 having a pivot 68c in plates 44 has a right-hand end 68a which arrests cradle 64 and a left-hand end 68b that rests on a latch 70 carried by the common trip bar 20. Compression springs 72 at the ends of bar 20 bias latch 70 toward the right as seen in Fig. 9. This latch is shifted toward the left by one or all of the bimets 22 in the respective poles, acting through an adjusting screw 74 in each of the poles carried by a respective bracket 76, joined to common trip bar 20. It is evident that, if any or all of the bimets 22 should deflect toward the left, trip bar 20 will rock counterclockwise so as to release latch 70, secondary latch 68 and cradle or releasable member 64. When this occurs, as is conventional, springs 52 swing member 64 counterclockwise. At the same time, springs 52 buckle the toggle by pulling its knee 54 past center, and springs 52 then are effective to swing moving contact-arm carriers 30 counterclockwise for swinging the contact arms 24 of all of the poles in the contact-opening direction. Manual lever 48 is also moved by springs 52 a short distance to the left of the position in Fig. 9 to provide the usual "trip indication."

When secondary latch 68 is released by its latch 60, and it attempts to rotate about its pivot 68c, it must also rotate a pendulous-mass delay element 78 pivoted at 80 by virtue of gear teeth interconnecting members 68 and 78. This delay element augments the inherent delay involved in the operation of a bimetal 22 (which takes time before it heats up and deflects) and the natural delay in the mechanical operation of the secondary latch and the rest of the automatic contact-opening mechanism. As will be seen, it is desirable for a certain minimum time delay to be provided for inhibiting the opening of the contacts during severe over-load conditions. With some mechanisms there may be enough natural delay, and the delay element 78 may be unnecessary and may be omitted.

After the circuit breaker has been released by an overload, resetting is necessary. This takes place when manual lever 48 is swung to the extreme left-hand position so that lever portion 48a swings cradle 64 for relatching, and the knee of the toggle 54 is urged to the left. Subsequent operation of lever 48 to the right for closing the contacts acts to straighten and overset the toggle 56-58.

A link 82 is pivoted to operating lever 48 and to a two-armed lever 84 that is carried by a pivoted square shaft 86 of insulation or insulation-sheathed steel. Shaft 86 extends across all the poles and is carried by suitable end and intermediate bearings in molded base 46. A roller 88 coacts with the rearward projection 40 of the movable contact arm 24 during the re-setting operation, for restoring the movable contact arm 24 to its normal condition in relation to its contact-arm carriers 30, following a peak-current contact-opening operation. The purpose of this reset linkage is to operate arms 24 from the configuration in Fig. 7 to that in Fig. 8, as will appear later. The adjoining poles are similarly equipped with rollers 88 carried by single-armed levers similar to lever 84 operated by portions of shaft 86 extending across those poles.

Returning once again to the individual contact pair of a single pole and its associated electrical elements which appear in Figs. 1, 3 and 4 it is seen that terminal 12 has a strap extension 90 that is spaced well below contact 18 and is sheathed in insulation 92. At its left-hand extremity as seen in Figs. 1, 3 and 4, the current path through strap 90 divides into a pair of spaced-apart

Insulated parallel vertical conductors 94, extended via horizontal insulated conductors 96 and via vertical insulated conductors 98, to be rejoined at a pedestal 100. The fixed contact 18 is mounted on pedestal 100.

A circuit may be traced through the circuit breaker as follows: Starting at terminal 10, the current follows a path through bimetal 22 of each pole, and then along the flexible braid 101 to the moving contact arm 24, through contacts 16 and 18, along conductors 98, 96, 94 and 90, ultimately to terminal 12. In a reversal of parts, the coil represented by conductors 90, 94, 96 and 98 could be interposed in series with the flexible braid so that the current would then pass from the bimetal through suitable braid to the coil, then by braid to moving contact arm 24 and ultimately to fixed contact 18 connected directly to terminal 12. In the arrangement shown, the coil is electrically at the potential of the terminal 12 during and after arc interruption, whereas in the other arrangement described, the coil is electrically at the potential of the moving contact arm 24.

Movable contact arm 24 moves between the two branch-circuit paths 94—96—98. If it is assumed that current is momentarily passing from left to right in the moving contact arm 24 in Fig. 1, then the current divides at pedestal 100 (Fig. 4) to travel along the conductors 96 and 90 according to the arrows which appear in Figs. 1 and 4.

For normal values of current there is a modest electrical interaction between the fixed coil 90—94—96—98—100 and the contact arm 24. However, for extreme overloads, severe instantaneous levels of current will produce electrodynamic action of considerable force. A force of attraction will exist between arm 24 and conductor 90 whereas a force of repulsion will exist between conductors 96 and contact arm 24. The net result is to drive contact arm 24 downward. Movable contact 16 rocks about its rear edge as illustrated in Fig. 5 and contact arm 24 moves bodily downward, slot 28 accommodating limited motion of arm 24 relative to pivot 26 during this operation. The stroke is sufficient, however, so that the spring pivot points 37 in member 24 moves over center, with respect to the extreme left-hand and the extreme right-hand reaction points 35 of those springs in member 30. The over-centering of these springs tends to drive member 24 counterclockwise about its pivot 26. However at this moment the electrodynamic force produced by current through member 24 having been great enough to over-center springs 34 and 36, is sufficient to overcome that opening spring bias. The degree of this over-centering may be adjusted so that the moving contact arm 24 starts its opening travel for separating contact 16 from contact 18 at an appropriate level of current during the declining portion of an alternating-current half-wave. The initial separation should occur sufficiently in advance of the zero cross-over of the alternating-current wave for consistent arc-interruption to be effected but it should not be so early as to cause excessive arcing.

Certain current directions were assumed in Figs. 1 and 4 to show the downward forces which are produced electrodynamically by heavy currents. The same forces, in the same directions, are produced during moments when the alternating current wave produces oppositely directed currents in all these conductors.

It may now be assumed that the current has declined sufficiently for springs 34 and 36 in one of the poles to swing its contact 16 away from the fixed contact 18. The moving contact of that pole will then appear as illustrated in Fig. 6. However, this condition applies to only one individual pole. The contact arms of the other poles will not open at this instant when used in a three-phase circuit. The current in the other poles is likely to be high (depending on the nature of the short circuit) at the instant that the current in the opened pole passes through zero. At this instant the contact arms in the adjoining poles will remain unaffected if their currents are

low or they will be held down during the remainder of the heavy-current portions of their current waves. If they are subjected to severe current overload, they will be released subsequently for opening in the manner indicated in Fig. 6.

Irrespective of whether there is a heavy current in only one of the poles or heavy currents in multiple poles, the current-responsive bimetal or bimetals will be heated and will cause operation of the common trip bar. In the contact operating mechanism in Fig. 9, all carriers 30 will be automatically operated in the contact opening direction. Each of the contact arms 24 that previously assumed the position of Fig. 6 due to a severe overload then assumes the position in Fig. 7. Those contact carrying arm 24 of poles not subjected to severe peak overload currents then appear as in Fig. 8.

It will be understood that the kind of overload which brings into play the electrodynamic action represented in Figs. 1 and 5 will ordinarily be a severe overload, of the order of ten to perhaps 100 times the tripping level for which the bimetals are designed to respond in the case of moderate overloads. For example, a circuit breaker whose bimetals are designed to trip the circuit breaker for a persistent 100 ampere overload current would normally not respond electrodynamically to produce the kind of operation represented in Figs. 5 and 6 except for much heavier currents. This type of operation could be made effective only when the current reaches something in excess of 1000 amperes or perhaps 1500 amperes as a minimum level. For currents below such electrodynamic tripping level, the bimetals would function as in conventional circuit breakers. Following a bimetal tripping operation, signifying either a persistent modest overload or a short-circuit, all of the contact carriers 30 would appear as in Figs. 7 and 8. The manual lever 48 conventionally moves to a trip indicating position. In addition to this "trip" indication, the present invention provides a "short indicator." A shaft 102 carried by cover 104 (Fig. 7) is provided with three members 106 having depending portions in the opening path of the respective contact-carrying arm 24 of its pole following a short-circuit tripping operation. The member 106 of the center pole is provided with a legend "Short" that is swung into view through an opening 108 in the cover 104. Normally, spring 110, acting between at least one of the members 106 and the cover 104, is effective to keep all of the members 106 in their normal position in which the "short" indication is rotated away from the window 108.

A review of the operation of the three-pole circuit breaker in a three-phase circuit may prove helpful to a better understanding of the basic and detailed concepts involved. Fig. 11 illustrates this application.

The three waves of alternating current A, B and C are shown displaced 120° in time. At a time (*t*) a short-circuit may develop. Let it be assumed to be a single-phase short-circuit, between one phase line and ground.

Considering phase A, the current that flows rises virtually immediately (depending on the nature of the distribution line) to $A(t)$. This is above the level (I) which represents the minimum current level effective to over-center springs 34 and 36 by electrodynamic action, and the pole of the circuit breaker carrying phase A shifts per Fig. 5. The hold-down electrodynamic bias continues to hold the contacts together, until the current drops to level (II), which is the point at which the opening spring bias of the springs 34 and 36 in the configuration of Fig. 5 is equal to the hold-down bias. Further decline of the current allows the over-centered springs to drive the contacts apart. The contacts separate far apart (Fig. 6) before the wave A reaches zero. The voltage wave will have little tendency to restrike an arc, because the ionization produced by the relatively low and declining current $A(t)$ is limited, compared to that which would develop if an attempt were made to interrupt the short-circuit.

current earlier in the cycle. This is self-evident where high levels of current are considered. It is perhaps less obvious were the interruption attempted with a low, but rising current. Such low current produces an arc that is sustained during the ensuing rise to peak current and during its decline to zero in a circuit breaker unaided by air blast or other special apparatus for breaking the arc. It is not enough to part the contacts when the current is low; it is important to open the contacts during the decline so that the arcing time before the zero cross-over is minimized, consistent with adequate separation of the contacts to avoid restriking.

If a single-phase short-circuit is considered to develop in phase B at time (t) , the same operation takes place that has been described for phase A. The contact arm 24 is electrodynamically shifted and the springs 34-36 are over-centered promptly, because the current at that instant exceeds level I. The contacts are held together and no arcing occurs until the current declines to level II at B(0), when the contacts start to part under spring bias, accompanied by limited arcing. Arc interruption is completed by the time of the zero cross-over.

A single-phase short-circuit in phase C at time (t) produces only moderate current flow at that instant. The current declines through zero and then rises. Only when the current reaches level I does the operation occur such as is described for phases A and B.

In each phase A and B considered separately, interruption occurs within a half cycle. In phase C a slightly longer time is needed as shown.

In the case of a two-phase short, and in three-phase shorts, various phase shifts occur between the short-circuit currents of the different phases A, B and C. However, the basic operation is not different from that described.

The bimets are heated by the current surge and cause tripping of all the poles whether they were involved in the short-circuit or not. The action of that trip-one-trip-all operation of the three-pole operating mechanism in Figs. 9 and 10 is inherently slower than the operation of the mechanism in Figs. 1 and 5-8. If there is any tendency for the three poles to trip together, faster than the individual electrodynamic tripping mechanism, suitable delay may be imposed, as by added delay element 78. The directly heated bimetal illustrated may also be replaced by conventional indirectly heated bimetals, for additional delay. It is desirable to have delay, but only enough to be sure that the trip-one-trip-all mechanism will not function during the short-circuit operation in any of the phases, as described.

The foregoing illustrative embodiment of the invention represents an exemplary form presently contemplated but it is naturally subject to varied modification and application; and consequently the invention should be broadly construed in accordance with its full spirit and scope.

Having thus described our invention, what we claim and desire to secure by Letters Patent is:

1. Current responsive contact opening means for use with alternating current, including a pair of separable contacts, spring actuated contact-opening means normally effective to close the contacts and having electrodynamically actuated means effective during a half cycle of overload current to change said spring actuated means into condition to bias the contacts in the opening direction in response to a predetermined instantaneous overload current level, electrodynamic contact biasing means including a conductor in series with the contacts effective to hold the contacts together during instantaneous current levels comparable to said predetermined level, despite conditioning of the contact-opening means to bias the contacts open, the bias of said electrodynamic biasing means declining during said half cycle and the electrodynamically conditioned spring actuated contact-opening means thereupon becoming effective to part the contacts.

2. Current-responsive, contact-opening means for use with alternating current, including a pair of separable contacts, and contact-opening mechanism including a current-responsive element responsive to a predetermined instantaneous level of overload current during an alternating-current cycle for conditioning said mechanism to open the contacts at a later time in the alternating current cycle when the current has declined to a more readily interruptable level, said mechanism also including current-responsive means arranged to oppose the opening force of the contact-opening mechanism and effective to hold the contacts together during the time when the current remains excessive and until it declines as aforesaid.

3. Current-responsive contact-opening means for use with alternating current, including a pair of contacts, one of said contacts being carried by a movable contact arm, electrodynamic means including said arm actuated by instantaneously high levels of current for biasing the contacts together, and spring-actuated contact-opening mechanism having electrodynamically actuated means responsive to short-circuit levels of instantaneous current during an alternating-current cycle for operating said mechanism to apply opening bias to the contacts, said electrodynamic means being arranged to act in the direction opposite said opening bias and with sufficient force to hold the contacts together during the flow of instantaneous levels of current in excess of that which is effective to activate the opening mechanism, the contacts thereafter opening at a time later in the alternating current cycle when the current has declined and the opening spring bias exceeds the reduced opposite-acting electrodynamic bias.

4. A current interrupter for alternating current, including a pair of contacts and operating means for closing and opening the contacts, said means including an over-center spring device normally biasing the contacts together when the contacts are closed, electrodynamic current-responsive means providing driving energy for over-centering the spring means during an alternating current cycle in response to an instantaneous level of excess current, thereby providing spring bias to contacts in the opening direction, and electrodynamic means acting opposite said over-centering spring means when over-centered for holding the contacts together during the flow of severe instantaneous levels of excess current and effective to hold the contacts together despite said opening spring bias, said overcentering spring means acting upon decay of the current to overcome the electrodynamic contact-holding effect and thereupon becoming effective to open the contacts.

5. Current-responsive contact-opening means including a pair of contacts, one of said contacts being carried by a movable contact arm, electrodynamic means for biasing the contacts together and spring-actuated contact-opening means including an element responsive to a predetermined instantaneous severe current level of an alternating current cycle for conditioning said mechanism to open the contacts later in the cycle after the current declines below the level for which said contact-holding means is effective, said electrodynamic biasing means being disposed to oppose the opening of the contacts by said contact-opening means.

6. Current-responsive contact-opening means for use with alternating current, including a pair of contacts, one of said contacts being carried by a movable contact arm, electrodynamic means for biasing the contacts together, contact-opening means including spring means acting on said arm directly and normally biasing the contacts together, and an element responsive to an instantaneous severe level of current in a cycle of alternating current for reversing the bias of said spring means so as to act in the direction to open the contacts but this spring bias being effective to cause actual parting of the contacts only later in the cycle after the current declines and the resulting electrodynamic bias falls below the spring bias.

7. Current-responsive contact-opening means for alternating current use, including a pair of contacts, one of said contacts being carried by a movable contact arm, electrodynamic means including said arm and fixed conductors in series with said contacts for biasing the contacts together, electrodynamic contact-opening means including an over-centering spring mechanism and a support for said contact arm allowing movement thereof about the contacts as a fulcrum in response to an instantaneous severely high level of current during a half-cycle of alternating current, and the over-centering spring-mechanism being over-centered by that movement of the arm so as to bias the contacts apart and the electrodynamic means including said arm and said fixed conductors being disposed to oppose said opening bias, actual contact separation occurring later within that half-cycle of alternating current when the electrodynamic bias has declined below the contact-opening spring bias.

8. Current-responsive contact-opening means for use with alternating current, including a pair of contacts, one of said contacts being carried by a movable contact arm, electrodynamic means including said arm responsive to the current therein for biasing the contacts together, and contact-opening mechanism including an element responsive to a predetermined high instantaneous level of current for promptly conditioning said mechanism to open the contacts at a later time in the alternating current cycle when said contact-holding means is overpowered by said contact-opening means, said electrodynamic biasing means being disposed to oppose the opening of the contact by said contact-opening means.

9. Current-responsive contact-opening means for use with alternating current, including a pair of contacts, one of said contacts being carried by a movable contact arm, electrodynamic means including said arm responsive to the current therein for biasing the contacts together, and contact opening mechanism including an element responsive to a predetermined high instantaneous level of current for promptly conditioning said mechanism to open the contacts at a later time in the alternating current cycle when said contact-holding means is overpowered by said contact-opening means, said conditioned contact opening mechanism and said holding means arranged to oppose each other and being related to each other to release the contact arm within an over-load half-cycle and at a time sufficiently in advance of the alternating current cycle passing through zero so that the contact arm has moved to space the contacts apart amply to avoid restriking of an arc.

10. Current-responsive contact-opening means for alternating current, including a pair of contacts, one of said contacts being carried by a movable contact arm, and manual operating means for said arm to open and close the contacts, said manual operating means including a carrier for said movable contact arm electrodynamic means actuated by instantaneously high levels of short-circuit current for biasing the contacts together, and spring-actuated contact-opening mechanism acting between said contact arm and said contact arm carrier and having electrodynamically actuated means responsive to an instantaneous short-circuit level of current for promptly conditioning said spring-actuated mechanism to open the contacts later in the same alternating current half-cycles when the current has declined below the level for which said electrodynamic biasing means is effective, the contacts thereupon opening while the manual operating means remains in its contacts-closed configuration said electrodynamic biasing means being arranged to oppose the opening of the contacts by said contact-opening mechanism.

11. Current-responsive contact-opening means for alternating current, including a pair of contacts, one of said contacts being carried by a movable contact arm, and manual operating means for said arm to open and close the contacts, said manual operating means including a

carrier for said movable contact arm electrodynamic means actuated by instantaneously high levels of short-circuit current for biasing the contacts together, and spring-actuated contact-opening mechanism acting between said contact arm and said contact arm carrier and having electrodynamically actuated means responsive to an instantaneous short-circuit level of current for promptly conditioning said spring-actuated mechanism to open the contacts later in the same alternating current half-cycles when the current has declined below the level for which said electrodynamic biasing means is effective, said electrodynamic means being arranged to oppose said contact-opening mechanism, the contacts thereupon opening while the manual operating means remains in its contacts-closed configuration, and an indicator operated in response to said electrodynamically actuated means to signal such opening of the contacts.

12. A multi-pole circuit breaker having, in each pole thereof, a pair of contacts and a current responsive tripping element, coordinated operating means controlled by said current responsive elements for causing the contacts of all the poles to move to their open positions in response to an overload in any of the poles, an individual spring-powered mechanism in each pole conditioned by an instantaneous current exceeding a predetermined heavy current level for driving its related contacts apart, and electrodynamic means in each pole disposed to restrain the thus conditioned spring-powered mechanism of that pole and effective to hold the contacts together during such current excess, the spring-powered mechanism being ineffective to part the contacts of that individual pole until after the current of that pole has declined and the electrodynamic holding force is overcome by the spring-powered means.

13. A multi-pole circuit breaker having, in each pole thereof, a pair of contacts and a current-responsive tripping element, operating means for all the poles to open and close the contacts thereof, coordinating means controlled by said tripping elements causing the contacts of all the poles to move to their open positions in response to an overload in any one or more of the poles, electrodynamic means in each pole for holding the contacts closed during moments when the instantaneous values of current exceed a predetermined heavy current level, and an individual spring-powered mechanism in each pole rendered effective by such heavy current levels for driving its related contacts apart after the current of that pole has declined sufficiently so that the electrodynamic holding means is overcome by the spring-powered means, said electrodynamic holding means being arranged to oppose the opening of the contacts by the spring powered means of the related pole only, said operating means and said coordinating means having an inherently slower operating time than said spring-powered mechanism so as to operate only after the operation of any individual spring-powered mechanism that is rendered effective by said predetermined excessive current.

14. A multi-pole circuit breaker for alternating currents, including a common operating mechanism for the several poles to open and close the contacts thereof and including a releasable member, a trip bar common to all of the poles in control relation to said releasable member, each pole including a pair of contacts, a current-responsive bimetal, and a movable contact-carrying arm for one of the contacts of that pole, electrodynamically controlled means operative individually on each arm for driving the contacts apart, said electrodynamically controlled means being conditioned to open the contacts in response to severe instantaneous current excesses and being operative to open the contacts later during such excess half-wave of alternating current when the current has declined and is approaching zero.

15. A multi-pole circuit breaker for alternating currents, including a common operating mechanism for the several poles to open and close the contacts thereof, a

tripping mechanism common to all of the poles operative to cause automatic opening of all the contacts in response to an overload, said mechanism providing a trip indication, each pole including a pair of contacts, a movable arm carrying one contact of said pair, a current-responsive device in control relation to said tripping mechanism, each pole also including an individually electrodynamically controlled means operative on the related contact arm individually for driving the contacts of that pole apart in response to a severe instantaneous current excess, and an indicator additional to said trip indication operated by any of said contact arms to evidence operation of the individual electrodynamic means in response to severe current excesses.

16. A multi-pole circuit breaker for alternating current use having, in each pole thereof, a pair of contacts and a current responsive tripping element, operating and coordinating means for opening and closing the contacts and for causing the contacts of all the poles to move to their open positions automatically in response to an overload in any of the poles, electrodynamic means in each pole for biasing the contacts closed, and an individual spring-powered mechanism acting directly on the contact carrying arm in each pole and rendered operative by a severe instantaneous current level for driving its related contacts apart before the mechanism-operating half-wave of alternating current has dropped to zero.

17. A multi-pole circuit breaker for polyphase circuits, including mechanism for concurrently operating the several poles to open and close the contacts thereof, a trip mechanism for automatically causing said operating mechanism to open the contacts of all the poles, a current-responsive element in each pole in control relation to said trip mechanism, and a contact-carrying arm for one contact of each pair of contacts, electrodynamic means operative to open the contacts of an individual pole in response to excessive current therein when the instantaneous current of that pole has declined, said contact-operating mechanism being thereafter effective after an inherent delay time for operating the contacts of all of the poles into their open-circuit positions, the delay time being long enough for each pole in the polyphase circuit to be operated electrodynamically.

18. A multi-pole circuit breaker for polyphase circuits, including a common operating mechanism for the several poles to open and close the contacts thereof and including a releasable member, a trip bar common to all of the poles in control relation to said releasable member, each pole including a pair of contacts, a current-responsive bimetal, and a movable contact-carrying arm for one of the contacts of that pole, electrodynamically actuated means including the related contact-arm to bias the contacts of each individual pole together during excessive levels of instantaneous current and for driving those contacts apart after the current has declined, said bimetal and said common trip bar and said common contact-operating mechanism being effective after an inherent delay time for opening the previously unopened contacts of all remaining poles, the delay time being sufficient to allow for the individual poles to be operated electrodynamically.

19. A multi-pole circuit breaker including operating mechanism for concurrently opening and closing the several poles, coordinated tripping means responsive to overload current in any of the poles to cause automatic opening operation of said operating means, and faster-acting electrodynamic means individual to each pole responsive to the current therein to open the contacts thereof.

20. A multi-pole circuit breaker including operating mechanism for concurrently opening and closing the several poles, coordinated tripping means responsive to overload current in any of the poles to cause automatic opening operation of said operating means, and faster-acting electrodynamic means individual to each pole and responsive only to currents of short-circuit level to open

the contacts thereof, said operating mechanism including means providing an indication of automatic opening of the contacts, and an additional indicator operated by said poles severally for signalling electrodynamic operation of an individual pole and thereby indicating occurrence of a short-circuit.

5 21. A multi-pole circuit breaker, including in each pole a pair of contacts, a movable arm for one of said contacts, and a contact-arm carrier, each contact-arm carrier pivotally supporting one of said contact arms, electroresponsive means for actuating each contact arm individually relative to its contact carrier to open the related contacts, and relatively delayed current responsive means for concurrently operating all said contact-arm carriers in the direction to carry the related contact arms in the contact opening direction.

10 22. A multi-pole circuit breaker especially adapted for polyphase circuits, including a pair of contacts in each pole, individual fast-acting short-circuit-current-responsive mechanisms in each pole for parting the contacts thereof at a favorable time in the current cycle of that pole independently of the individual mechanisms of other associated poles of the multi-pole circuit breakers and of the phase of currents that may be carried thereby, and relatively slow-acting mechanism responsive to both moderate overloads and short-circuit currents for concurrently operating all the poles in the contact-opening direction and thereby parting the contacts of poles not previously opened by one of said individual short-circuit-current-responsive mechanisms.

15 23. Current-responsive contact-opening means for alternating current, including a pair of contacts, one of said contacts being carried by a movable contact arm, and manual operating means for said arm to open and close the contacts, said manual operating means including a carrier for said movable contact arm, electrodynamic means actuated by instantaneously high levels of short-circuit current for biasing the contacts together, and spring-actuated contact-opening mechanism acting between said contact arm and said contact arm carrier and having electrodynamically actuated means responsive to said instantaneous short-circuit level of current for promptly conditioning said spring-actuated mechanism to open the contacts later in the same alternating current half-cycle when the current has declined below the level for which said electric-dynamic biasing means is effective, the contacts thereupon opening while the manual operating means remains in its contact-closed configuration, said manual operating means including a reset device for restoring said spring-actuated contact-opening mechanism to its contact-closing configuration while the manual operating means is in its contacts-open configuration.

20 24. A multi-pole circuit breaker for alternating currents, including a common contact-operating mechanism for the several poles to open and close the contacts thereof, a tripping mechanism common to all of the poles operative to cause automatic opening of all the contacts in response to an overload, each pole including a pair of contacts, a movable arm carrying one contact of said pair, a current-responsive device in each pole in control relation to said common tripping mechanism, and each pole further including an individually electrodynamically controlled means operative on the related contact arm individually for providing energy for conditioning the contacts of that pole to be driven apart in response to a severe instantaneous current excess.

25 25. Current-responsive contact-opening means for use with alternating current, including a pair of contacts, one of said contacts being carried by a movable contact arm, electrodynamic means for biasing the contacts together, contact-opening means including spring means acting on said arm directly and normally biasing the contacts together, and means including an element arranged electrically in series with said contacts for electrodynamicly

providing the driving force in response to an instantaneous severe level of current during any half-cycle of alternating current for reversing the bias of said spring means so as to act in the direction to open the contacts but this spring means being effective to cause actual parting of the contacts only later in the half-cycle after the current declines and the bias resulting from said electrodynamic biasing means declines below the spring bias in the contact-opening direction.

26. A multi-pole circuit breaker for alternating currents, including contact-operating mechanism for the several poles to open and close the contacts thereof, overload responsive means including a current-responsive element in each of the poles operative to effect operation of said contact-operating mechanism for automatic opening of all the poles substantially simultaneously in response to an overload in any pole, each pole including a pair of contacts, a movable arm carrying one contact of said pair and each pole further including an individually electrodynamically controlled means operative on the related contact arm individually for supplying energy for conditioning the contacts of that pole to be driven apart in response to a severe instantaneous current excess therein.

27. A multi-pole circuit breaker for alternating current, including in each pole a single-poled overload current-responsive release means, a pair of contacts, and mechanism released under control of any one or more

of the single-pole overload responsive means for effecting opening of the contacts of all the poles substantially simultaneously, each pole including an arm carrying one contact of the related pair of contacts, electrodynamic means biasing the contacts thereof together, contact-opening means including spring means acting on said arm directly and normally biasing the contacts of that pole together, an element arranged electrically in series with the contacts of each pole and responsive to an instantaneous severe level of current in a cycle of alternating current for reversing the bias of said spring means so as to act in the direction to open the contacts of that pole but this spring bias being effective to cause actual parting of the contacts of that pole only later in the cycle after the current therein declines and the resulting electrodynamic bias falls below the spring bias.
